UNITED STATES PATENT OFFICE.

WILLIAM ALEXANDER TAYLOR, OF FRENCH CAMP, MISSISSIPPI, ASSIGNOR
OF ONE-HALF TO JAMES A. SANDERSON, OF FRENCH CAMP, MISSISSIPPI.

PLOW ATTACHMENT FOR SIDE HARROWS.

SPECIFICATION forming part of Letters Patent No. 710,629, dated October 7, 1902.

Application filed July 14, 1902. Serial No. 115,505. (No model.)

To all whom it may concern:

Be it known that I, WILLIAM ALEXANDER TAYLOR, a citizen of the United States, residing at French Camp, in the county of Choctaw and State of Mississippi, have invented 5 a new and useful Plow Attachment for Side Harrows, of which the following is a specification.

This invention relates to harrows and is 10 designed to provide a plow attachment which may be conveniently applied to an ordinary side harrow, so as to travel in rear of the teeth thereof, and is readily detachable when not required for use.

15 Another object is to provide for applying and removing the attachment without interfering with or removing any of the parts of the harrow-frame, so as to greatly facilitate the application and removal of the attachment.

20 Another object is to have the attachment conveniently adjustable, so that it may be shifted to the right and left and also raised and lowered to regulate the depth of operation of the plow.

25 With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made 30 within the scope of the claims without departing from the spirit or sacrificing any of the advantages of the invention.

35 In the drawings, Figure 1 is a plan view of an ordinary side harrow having the present attachment applied thereto. Fig. 2 is a side elevation thereof. Fig. 3 is a detail sectional view on the line 3-3 of Fig. 1 to show the connection between the beam of the attachment and the tooth-bar of the harrow. Fig. 4 is a perspective view of the attachment removed 40 from the harrow.

45 Like characters of reference designate corresponding parts in all of the figures of the drawings.

Referring at first more particularly to Fig. 50 3 of the drawings, it will be seen that the present attachment is made up of a beam 1,

having a standard 2 pendent from its rear end and preferably consisting of a downwardly-bowed integral terminal extension of the beam. A suitable shovel-plow 3 is 55 connected to the lower end of the standard in any preferred manner. At the front end of the standard there is an integral upstanding eye 4, the top and bottom of which are embraced by a clevis 5, having its pin or bolt 60 6 passed through the opposite ends of the clevis and also the eye of the beam, whereby the latter and the clevis are pivotally connected. A suitable nut 7 is applied to the lower end of the clevis pin or bolt 6, so as to prevent 65 accidental displacement thereof and to permit convenient removal of the pin whenever desired. A pair of brace-bars 8 rise from the rear end portion of the beam, with their lower ends lying at opposite sides of the beam and 70 connected thereto by a suitable fastening 9, from which the braces diverge and incline forwardly and have their upper ends provided with a longitudinal series of perforations 10.

75 For an understanding of the application of the device of the present invention reference is had to Figs. 1, 2, and 3 of the drawings, wherein it will be seen that the clevis 5 embraces the rearwardly-inclined tooth-bar 11 of an ordinary side harrow, with its ends projected slightly in rear thereof and embracing the eye 4 of the plow-beam, the clevis-pin 6 being passed through the ends of the clevis and the eye 4, so as to form a pivotal or hinged connection between the beam and the 80 tooth-bar. The brace-bars 8 incline upwardly across the inner sides of the handle-bars 12, to which they are connected by means of suitable fastenings—as, for instance, the fastenings 13, which secure the 85 braces 14. Should it not be desirable to secure the brace-bars by means of the fastenings 13, they may be secured by independent fastenings. By reason of the series of perforations 10 the brace-bars may be adjusted 95 vertically, so as to give a corresponding adjustment to the plow-beam for regulating the depth of operation thereof. Moreover, the plow can be shifted toward either side of the harrow by moving the clevis longitudinally 100 thereof. In shifting the beam to one side or the other the upper ends of the brace-bars 8

are adjusted accordingly upon the handles of the harrow—that is to say, one of the bars is shifted upwardly and the other downwardly—in order that the beam may be properly braced in whatever position it may be placed.

From the foregoing description it is apparent that the device of the present invention is complete in itself and is constructed and arranged so as to be conveniently applied and removed from the tooth-bar of a side harrow without removing or interfering with any of the parts of the latter. With my attachment applied to the harrow two operations are performed at the same time by means of a single implement and a single horse or team, and it will be found that the harrowing of the ground will be more thorough and satisfactory than when the plow is carried by a separate implement drawn by a separate horse or team.

What I claim is—

1. The combination with a harrow having a transverse tooth-bar, of a beam having its forward end detachably connected to the tooth-bar, and provided with a standard, and a plow carried by the standard.

2. The combination with a harrow having a transverse tooth-bar, of a plow-beam having a standard and a plow carried thereby, and a clevis embracing the tooth-bar and pivotally connected to the beam.

3. The combination with a harrow and the handles thereof, of a plow-beam projected rearwardly from and having a loose connection with the harrow, a plow carried by the beam, and vertically-adjustable braces rising from the beam and connected to the handles.

4. The combination with a harrow, of a plow-beam hinged thereto and capable of being adjustably swung transversely of the harrow, a plow carried by the beam, and adjustable braces extending from opposite sides of the beam to the harrow.

5. The combination with a harrow having

a transverse tooth-bar and handles above the bar, of a plow-beam projected rearwardly from the bar and having a standard and a plow carried thereby, the front end of the beam having an eye, a clevis embracing the tooth-bar and the eye of the plow-beam, a pin passed through the clevis and the eye, braces rising from the beam to the handles with their upper ends provided with perforations, and fastenings piercing the handles and corresponding perforations of the braces.

55

6. A plow attachment for harrows, comprising a beam, a standard pendent therefrom, a pair of braces rising from the beam, and provided with means for connection with a harrow, and means carried by the forward end of the beam for detachable connection with a harrow.

60

7. A plow attachment for harrows, comprising a beam having a standard, braces rising from the rear end portion of the beam and provided at their upper ends with perforations, fastenings for interchangeable engagement with the perforations to connect the braces to a harrow, a clevis embracing the forward end of the beam, and a pivot-pin 70 piercing the ends of the clevis and the beam.

65

8. The combination with a harrow having a transverse toothed bar which is made up of upper and lower spaced members, of a beam having its forward end inserted between the members of the toothed bar, a clevis embracing the toothed bar and the beam, a pin piercing the ends of the clevis and the beam and located in the rear of the toothed bar, and a plow carried by the beam.

75

In testimony that I claim the foregoing as my own I have hereto affixed my signature in the presence of two witnesses.

WILLIAM ALEXANDER TAYLOR.
